WOMEN'S SHORTS FOR OUTDOOR WEAR
Dorothy M. Overholt, St. Petersburg, Fla.
(1720 Miami Court, Fort Pierce, Fla.)
Filed June 27, 1963, Ser. No. 280,887
3 Claims. (Cl. 2-238)

This invention relates to nether garments and more particularly to a garment in the general nature of a pair of shorts for outdoor wear such as are widely used today by girls and women as the lower half of a sunsuit, etc.

In recent years there has been a great demand in the warmer climates and seasons for women's shorts which are both functional and at the same time attractive in appearance.

Women's bathing suits—as distinguished from shorts which are intended to cover only the bottom portion of the torso—provide a greater range as to overall appearance but almost invariably there is an underneath portion which while sewed in place is in the form of a separate tight-fitting pantie or the like which restricts body movement, etc.

It is among the objects of the present invention to provide an up-to-date nether garment for women which is designed for maximum comfort and attractiveness without sacrifice to modesty.

Another object is the provision of an improved garment of the type described which, in addition to the attributes described hereinbefore, is somewhat flexible as concerns the size and shape of the wearer, thereby permitting its being made up commercially in a minimum range of sizes, such as Small, Medium and Large.

Other objects and advantages of the invention will become apparent as the description of same proceeds and the invention will be best understood from a consideration of the following detailed description taken in connection with the accompanying drawings forming a part of the specification with the understanding, however, that the invention is not confined to a strict conformity with the showing of the drawings but may be changed or modified so long as such changes or modifications mark no material departure from the salient features of the invention as expressed in the appended claims.

In the drawings:

FIGURE 1 is a plan view of a substantially planar development of the novel nether garment of the present invention and illustrating the position of the feet of the wearer immediately prior to the application of the garment to the body;

FIGURE 2 is an elevational view illustrating the first step in applying the garment, the same comprising the positioning of the front panel over the abdomen, extending the strip ties thereof rearwardly, and tying the latter at a position which is adjacent the small of the back;

FIGURE 3 is view approximating a side elevation and illustrating the manner of drawing the rear or back panel between the legs and positioning the same over the buttox;

FIGURE 4 is a view similar in nature to that of FIGURE 2 and illustrating the front panel in position with the extending side portions of the rear panel in position for movement forwardly around the body of the wearer;

FIGURE 5 is a view illustrating the final disposition of that area of the extending portion of the rear panel which is first secured in position on the body; and

FIGURES 6 and 7 are front and rear views respectively of the garment as worn.

Referring more particularly to the drawings, the novel nether garment of the present invention comprises a front panel 2 and a back or rear panel 3, the same being connected by a relatively narrow crotch panel 4.

2

As will be observed in FIGURE 1, wherein the novel nether garment is shown in a substantially planar development, the side edges of the front panel 2 and the side edge of the back or rear panel 3 are reversely curved as indicated at 2a-2b and 3a-3b, respectively; and merge into concave side edges 4a of the crotch panel 4.

The front panel 2 is symmetrical about a center-line extending transversely of the width thereof. That is to say, its portions lying at either side of the center-line are the same in size and shape.

The back or rear panel 3 is substantially wider than the front panel 2 in both transverse directions; and is asymmetrical, the left-hand side thereof as viewed in FIGURE 1 extending outwardly from the longitudinal center-line for a greater distance than the right-hand side.

Tying strips 12 are secured to and extend from the outer corners of the front panel 2 and are adapted to be tied together by the wearer at the small of the back, preliminary to moving the remainder of the garment rearwardly between the legs and then raising the back or rear panel 3 into position. As aforementioned, this step is represented in FIGURE 2.

After moving the back or rear panel between the legs and then upwardly over the buttocks the narrower side of the back or rear panel 3 is positioned as shown at the right-hand side of FIGURE 4 and then moved forwardly around the left side of the wearer and overlapping the front panel 3 to a position which is approximately midway between the crotch area and the right hip bone. Thus, the lower end of this portion which extends from the rear panel 3 covers the crotch area.

Adjacent the waistline of the wearer the outside of the front panel 2 is provided with one or more fastening elements 15 (see FIGURES 2 and 4) which cooperate with similar elements 16 on the upper end of the extending portion of the narrower side of the back panel 3.

The outer surface of the narrower side of the front panel 3 has a tying strip 20 attached thereto at a position which is adjacent the left hip bone of the wearer, the same being adapted for cooperation with a tying strip 21 which is sewed to and extends from the upper end of the extending portion of the wider side of the rear or back panel 3.

As shown most clearly in FIGURE 6, the wider side of the rear panel 3 extends around the right side of the wearer, over the abdomen and onto the left-side to overlap with the previously positioned narrower side of the back panel, etc., and terminates in a generally vertical but sloping side edge 3c which extends upwardly from a position adjacent the central portion of the frontal area of the upper left leg to a position which is adjacent the left hip bone.

When applied to the body of the wearer in the manner described, the lower terminal ends of the extending portions of the back panel 3 provide curved edges 3a as shown in FIGURE 6; and the crotch panel 4 and the adjacent portions of the body of the wearer are covered.

Tucks 25 and other well known tailoring features are employed where desired.

As illustrated in FIGURES 6 and 7, the garment resembles a short skirt in front and a pair of shorts in the rear.

When applied to the human figure the novel garment is self-supporting, provides a double cover for the waist and upper portions of the legs and but a single cover for the buttocks. It possesses no vertical seams; and nowhere on it is there a meeting, or coming together of fabric, as would be the case in a pant leg. Accordingly, there is no restriction in the physical activity of the wearer.

While I have shown and described certain specific embodiments of the present invention, it will be readily

understood by those skilled in the art that I do not wish to be limited exactly thereto, since various modifications may be made without departing from the scope of the invention as defined in the appended claims.

I claim:

1. A self-supporting nether garment comprising front and back panels connected by a narrow crotch portion, the side edges of said front and back panels, when the garment is in an extended condition, being reversely curved and merging into concave side edges delineating said narrow crotch portion; said front panel being substantially symmetrical about a center-line extending transversely of the width thereof and sufficient in size and shape to substantially cover the abdomen and crotch area of the wearer; the upper and outer ends of said front panel, when worn by the wearer, terminating in narrow bands which extend rearwardly about the waist and which may be secured together in such manner as to entirely support said front panel; said back panel being of substantially greater overall width than the width of said front panel and asymmetrical about a center-line extending transversely of the width thereof; the narrower side of said asymmetrical back panel being adapted to extend partially around the body of the wearer and terminate between the crotch area and the right hip bone; the wider side of said back panel being adapted to substantially overlap the immediately aforementioned portion of the narrower side of the back panel and terminate in a generally vertical edge which commences in front of the mid-portion of the

left leg of the wearer and slopes upwardly and rearwardly to adjacent the left hip bone; means for securing the upper end of the narrower side of said back panel to the adjacent portion of said front panel; and means for securing the terminal end of the wider side of said back panel to the narrower side panel while in said overlapping position; the narrower side of said back panel being of approximately the same height as the wider and overlapping side thereof.

5 2. The combination of claim 1 wherein the lower ends of the terminal edges of both the narrower and wider sides of said back panel are convexly curved.

10 3. The combination of claim 1 wherein the narrow bands which extend from the upper and outer ends of said front panel about the waist of the wearer are of such size and shape as to permit of their being readily tied together.
